(57) **CLAIM**

The ornamental design for a fluid sump with internally mounted pump and filter housing, as shown and described.

DESCRIPTION

FIG. 1 is a perspective view of a fluid sump with internally mounted pump and filter housing according to the present invention;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.
